STAPLE DRIVING MACHINE

Fridolin Polzer and Roy E. Peterson, Norwalk, Conn., assignors to The E. H. Hotchkiss Company, Norwalk, Conn., a corporation of Connecticut

Application May 1, 1939, Serial No. 270,970

15 Claims. (Cl. 1-3)

This invention relates to a staple driving machine, such for example as is used for driving substantially U-shaped staples, and may be used as a so-called stapling machine to drive and clinch the staples or as a so-called tacking machine to drive the staples through articles to be attached to wood or similar material without clinching. It is a further development of and improvement on the construction disclosed in our prior application with Lester L. Wheeler, Serial No. 209,886, filed May 25, 1938.

An object of the invention is to provide an improved and simplified construction of staple driving machine, and one which may be made almost entirely as a press job and with parts welded together, thus eliminating the use of castings and making a lighter and stronger construction for the amount of metal used.

With the foregoing and other objects in view we have devised a construction as illustrated in the accompanying drawings forming a part of this specification, but it will be understood that various changes and modifications may be employed within the scope of the invention.

In these drawings:

Fig. 1 is a side elevation of a completed machine;

Fig. 2 is a longitudinal vertical section;

Fig. 3 is a longitudinal section immediately below the top wall of the operating lever 69 and the top wall of the back 6 of the housing looking down on the device;

Fig. 4 is a detail vertical section of the rear end portion of the machine showing the staple slide in a somewhat advanced position from the normal position of Fig. 2;

Fig. 5 is a front elevation of the staple driver showing the operating handle in section substantially on line 5-5 of Fig. 2;

Fig. 6 is a longitudinal vertical section through the front portion of this handle and driving lever;

Fig. 7 is a top plan view showing the staple slide projected to the loading position and showing a part of the body in section;

Fig. 8 is a partial side view and partial section of the parts shown in Fig. 7;

Fig. 9 is a transverse section substantially on line 9-9 of Fig. 7;

Fig. 10 is a bottom plan view of the front portion of the slide;

Fig. 11 is a bottom plan view of the body of the device with the staple slide removed;

Figs. 12 and 13 are transverse sections of the lower part thereof substantially on lines 12-12 and 13-13 respectively of Fig. 11;

Fig. 14 is a vertical section substantially on line 14-14 of Fig. 2;

Fig. 15 is a perspective view of the staple driver;

Fig. 16 is a top plan view of the follower on the staple slide;

Fig. 17 is a longitudinal vertical section of the front portion of the machine similar to Fig. 2 showing the plunger in the lower position and the rear portion of the machine being shown in elevation;

Fig. 18 is a vertical cross section substantially on line 18-18 of Fig. 2;

Fig. 19 is a vertical cross section substantially on line 19-19 of Fig. 2;

Fig. 20 is a vertical longitudinal section on an enlarged scale of the rear portion of the slide substantially on line 20-20 of Fig. 21;

Fig. 21 is a longitudinal section thereof substantially on line 21-21 of Fig. 20;

Fig. 22 is a section similar to Fig. 20 showing the staple slide released and moved forward a short distance;

Fig. 23 is a transverse section substantially on line 23-23 of Fig. 20;

Figs. 24, 25 and 26 are a side elevation, bottom plan and end view respectively of the reinforcing channel for mounting the body on the base;

Fig. 27 is a bottom view of the base with a portion broken away to more clearly show the construction;

Fig. 28 is a top plan view of the anvil;

Fig. 29 is a transverse section thereof substantially on line 29-29 of Fig. 28;

Fig. 30 is a section thereof substantially on line 30-30 of Fig. 29;

Fig. 31 is a similar section substantially on line 31-31 of Fig. 29;

Figs. 32 and 33 are a top plan view and side elevation respectively of the anvil selecting spring; and

Fig. 34 is a detail section substantially on line 34 of Fig. 2.

The device comprises a body 1 which is composed of upright side plates 2 and 3 forming side walls connected at their forward ends by a front wall 4, these three walls being made in one piece stamped from sheet metal of suitable gauge and formed or folded to shape with the side walls 2 and 3 in substantially parallel relation. At the rear ends the side walls 2 and 3 have inwardly turned integral ears 5 (Figs. 2, 3 and 11) which abut as shown in Fig. 3 and form a cross wall for securing a back cover 6. This cover is stamped from sheet metal and is of substantially

inverted U-shape in cross section providing flanges 7 to fit down over the top edges of the side walls 2 and 3, and the top edge portions of the walls 2 and 3 toward the rear of the device may be pressed inwardly or recessed as indicated at 8 (Figs. 2, 3 and 19) to receive these flanges 7, at least at the rear portion thereof to give a better appearance and permit the color to be narrowed at the rear end. The top wall of the cover 6 passes down over the ears 5 as shown in Fig. 2 and has an inwardly directed hook 9 engaging under the lower edge of these ears to hold the cover in place. The front end of the top wall of cover 6 is bent downwardly as shown at 10 to engage over the forward end of transverse ears 11 integral with the side walls 2 and 3 and may be bent back under these ears to hold this cover in place.

At the lower part of the body and between the side walls 2 and 3 is mounted a slide housing 12. This is of substantially rectangular shape in cross section as shown in Figs. 12 and 13, and has vertical side walls 13 located between the side walls 2 and 3 of the body or housing 1 and to which they are secured by any suitable means, preferably by spot welding at suitably spaced points along the slide housing as indicated at 14, Fig. 12. The side walls 13 are connected by an integral top wall 15, and the lower edges of the side walls 13 are bent inwardly to form flanges 16, but their free edges are spaced laterally to form a longitudinal slot 17. At suitable intervals integral lugs 18 project laterally from the flanges 16 and seat in notches 19 in the lower edges of the side walls 2 and 3 of the housing to help properly position the slide housing 12.

This slide housing 12 (Figs. 2, 17 and 18) encloses the slide 20 for supporting and guiding the staple strip 21. This slide is also formed from suitable gauge sheet metal and bent to substantially U-shape forming upright side walls 22 and a connecting bottom wall 23. This slide is mounted within the slide housing 12 so as to slide longitudinally therein, and is supported on the lower flanges 16 of this housing. The lower wall 23 of this slide is provided with downwardly pressed lugs 24 projecting into the longitudinal slot 17 between the flanges 16 and are of a width substantially the width of this slot so as to be guided by the edges of the flanges 16 and retain the slide centrally within the housing 12. The side walls 22 are spaced from the side walls 32 of the housing as shown in Fig. 9 to provide spaces for passage of the prongs of the staples and the side walls of the staple feeding follower 36. Mounted at the forward end of this staple slide 20, Fig. 8, and spaced a short distance from the end of the slide is an upright front plate 25 forming with the front end wall of the slide a guideway 26 for the staples to be driven and also a guide for the staple driver 27. This front plate 25 extends between the side walls 28 of a front plate cover 29, these side walls being connected by an integral front wall 30. This front plate cover 29 is mounted on a substantially U-shaped support 31 which has upright side walls 32 secured to the inner sides of the side walls 28 by soldering or welding, and the front plate 25 is secured to the front edges of these side walls and may also be secured to the side walls 28 of the cover by soldering or welding. The lower wall 33 of this U-shape support 31 may have notches 34 (Figs. 7 and 10) to form clearance for the prongs of the staple should these prongs be bent slightly backward and thus permit passage of the staple under these conditions without

clogging the machine. The support 31 may be secured to the slide 20 by any suitable means, but preferably by welding as indicated at 35.

Mounted to slide on the staple slide or guide 5 23 is a follower 36 of substantially inverted U-shape having side walls 37 extending downwardly on the outer sides of the side walls 22 of the slide with the connecting top wall 38 resting on the top edges of the side walls 22. This top 10 wall is depressed as indicated at 39 in Figs. 8 and 17 to form a groove or recess to receive a follower catch 40. At the forward end of this depressed 15 portion 39 the follower is provided with an opening 41 through which the catch 40 extends under the forward portion of the top wall 38, and the front end of this catch is bent upwardly as shown at 42 and extends through an opening 43 (Figs. 8 and 16) in the top wall 38 of the follower 20 to form a stop catch to engage a stop shoulder 44 formed in the underside of the top wall 15 of the housing 12. This shoulder may be formed by pressing up a portion of this top wall as indicated at 45 (Figs. 2 and 8). As will be seen in Fig. 8 engagement of the lug 42 of the 25 catch with the shoulder 44 will limit outward movement of the slide 20 because on the top edges of the side walls 22 of this slide are provided shoulders 46 which engage the rear end of the follower 36. At the rear end of the catch 40 it is bent downwardly as shown at 47, and this 30 wall is forked so that the wall extends downwardly on opposite sides of the follower rod 48. On this rod is a light coil spring 49 engaging this downwardly extending wall 47 and tends to push the follower 36 forwardly to feed forwardly the 35 staple strips and bring the individual staples at the forward end of this strip to the driving position under the driver 27 and over the guideway 26. At its rear end this follower rod 48 is secured to inwardly and transversely extending walls 50 integral with and forming extensions of the side walls 13 of the slide housing 12 as shown in Figs. 20, 21 and 22, the end of the rod being headed over as indicated at 51.

During normal operation the slide 20 carrying 45 and guiding the staple strip 21 lies within slide housing 12 as shown in Fig. 2 with the staple guideway 26 under and in alignment with the staple driver 27, and this slide is secured in this position by a pivoted slide release lever 52 forming a catch. This lever is pivoted by means of a cross pin 53 in two upstanding lugs 54 struck up from and integral with the walls of the slide housing 12 as shown in Fig. 34. The release lever 52 is stamped and formed from heavy sheet metal of suitable gauge, and has two side members 55 connected by an inverted U-shaped cross piece 56 which projects through an opening in the top wall or cover 6 of the body to form a thumb piece to operate the release lever 52. The 50 rear ends of these side walls 55 normally seat in notches 57 formed in the top edges of the side walls 22 of the slide 20 to retain the slide within the housing as shown in Fig. 2, this lever being held in this position by a spring 58 seated at one 55 end on projections 59 of the side walls 55 as shown in Figs. 2 and 3. The other end of this spring 58 embraces lugs 60 on the rear end portion of a driving lever 61.

This lever 61 is also made of heavy sheet metal of a substantially inverted U-shape in cross section, the side walls 62 of which are bent inwardly toward each other and then side by side to provide the lugs 60 and a seat for the end of the spring 58. The lever is pivoted on the cross pin 63 extending through the side walls 62 and the

side walls 2 and 3 of the body. The staple driver 27 is mounted on the forward ends of the side walls 62 as shown in Figs. 2 and 5, these walls being provided with notches 64, (Figs. 2 and 6) providing supporting lugs 65 at the lower side thereof on which the driver 27 rests, the side edges of this driver being provided with notches 66 as shown in Figs. 5 and 15 through which the lugs 65 project so that the top walls of the notches 66 rest on the top edges of the lugs 65. The upper end 67 of the driver is in the upper part of the notch 64, and the upper wall of this notch overhangs and projects downwardly somewhat as shown at 68 to retain the driver in the notch 64. As the lever 61 is depressed to force the driver 27 downwardly to drive a staple the lugs 65 may move laterally with respect to the plane of the driver to accommodate the required motion due to the fact these lugs swing about the pin 63 as a pivot. Force for operating the driver to drive the staple is secured by pressure of the top of the notch 64 on the top end of the driver.

An operating handle 69 is secured to and embraces the upper portion of the lever 61. This handle is of substantially inverted U-shape stamped and formed from proper gauge sheet metal with its connecting wall resting on the top of the connecting wall 70 of the lever 61 and to which it is secured by any suitable means such as spot welding 71 (Fig. 2). This top wall 70 at its forward end is bent downwardly between the side walls 62 as shown at 72, and backwardly at its lower edge as shown at 73 to form a stop to engage under a forwardly projecting stop 74 on a strap 75 mounted at 76 on the top wall of the housing 12, it being secured to this housing by any suitable means, preferably by welding it thereto. The engagement of the portion 73 against the stop 74 limits the upper movement of the lever 61 and the driver 27 under action of the spring 58 when pressure on the handle 69 is released. It will be understood that pressing downwardly with the hand on the handle 69 will rock the lever 61 about its pivot 63 and force the driver 27 downwardly in the guideway 26 to force the staple in this guideway into the work to be stapled, this staple during this movement being guided by the front end of the slide 20 and the front plate 25. The driver 27 is further guided by the front end of the top wall 15 of the housing 12 being bent upwardly as shown at 78 and the rear end of the front wall 4 of the body being bent backwardly and upwardly as indicated at 79, the two walls 78 and 79 being spaced slightly greater than the thickness of the driver 27. Downward movement of the handle 69 is limited by engagement of its top wall with the top edges of side walls 2 and 3 and front wall 4.

When it is desired to place more staples on the slide 20 the operator presses upon the thumb piece 56 removing the rear ends of the side walls 55 from the notches 57 in the slide 20 so that the slide 20 can then be moved forwardly to the position shown in Figs. 7 and 8, where it is exposed to permit placing of a new staple strip 24 upon this slide.

As shown more clearly in Figs. 20 to 23 a slide ejector spring 80 is mounted between the rear end of the slide 20 and the rear wall 50 of the housing 12. This spring has a lower portion located between the end of the bottom wall of the slide and the wall 50 so as to be engaged by this lower end of the slide and compressed when the slide is pushed in to its innermost position.

The rear end of the spring is bent upwardly as shown at 81 and looped about the follower rod 48 to retain the spring in position and also form an abutment against the rear wall 50. It will be apparent that as the spring 80 is compressed, when the lever 52 is released this spring 80 will immediately force the slide 20 forwardly a short distance acting as a sort of ejector to move the slide out sufficiently so that it may be grasped by the hand and drawn out to the full extended loading position of Figs. 7 and 8. The follower and staple feed spring 49 also tends to push the slide outwardly as it presses against the follower 36 tending to push it forwardly and presses the front end of the staple strip 24 against the front plate 25. Forward movement of the slide is limited by catch 42 (Fig. 3) engaging the shoulder 44, and the parts are so arranged that the follower is stopped just short of the guideway 26, that is, with its forward end in alignment with the rear wall of the guideway so that the follower does not extend across this guideway to be injured by operation of the driver 27. It is, however, to be desired that the slide 20 be not shot out rapidly to the extended position. Therefore it is provided with a brake spring 82 (Figs. 2, 20 to 23). This is a spring wire of general U-shape having the ends 83 of its side walls bent laterally and seated in openings 84 in the side walls 22 of the slide and the straight portion adjacent these ends as shown at 85 resting on the bottom wall of the slide, with a looped portion bent upwardly as shown at 86 arranged so that when the slide is in its innermost position it projects through the opening 87 in the top wall of the housing 12 (Figs. 20 and 23) through which the side walls 55 of the release lever project. As soon as the slide is forced forwardly however this free end 86 of the spring is depressed by the top wall 15 of the housing as shown in Fig. 22 thus placing the spring under tension, and as it rubs along the underside of this wall it forms a brake to prevent the slide being shoved outward rapidly to the extended position, and the spring may be sufficiently strong to hold the slide against further movement after it has been ejected a short distance by action of springs 80 and 49 so that the slide will have to be drawn out the rest of its movement by the operator.

When the device is used as a so-called tacker to merely drive staples through an article to be attached to another article no anvil or clinching means is required and the structure so far described may be used as such tacker. However, if it is to be used as a stapling machine to clinch the staples then it is used with an anvil for bending the prongs of the staple against the undersides of the articles to be attached together. In the present case such an anvil is indicated at 88 mounted in a base 89 immediately under the driver 27. Both the anvil and the base are made of stampings and formed to the proper shape. The anvil is longitudinally curved as shown in Figs. 2, 30 and 31 and has two sets of recesses 90, 91 and 92 (Fig. 28), the recesses 90 being shaped to bend the prongs inwardly toward each other to make a so-called permanent clinching while the recesses 91 and 92 give a so-called temporary clinching or setting, the recess 91 turning one prong inwardly and the recess 92 turning the other prong outwardly making the staple more easy to remove from the work. This anvil is mounted so that it may be shifted to bring either set of recesses in alignment with the staple driv-

er 27. It is mounted in an opening 93 in the top wall of the base the walls of the opposite sides of this opening being depressed to form supporting lugs 94 on which the anvil rests, the opposite sides of the anvil being bent downwardly to form flanges 95 resting on these lugs 94. The top surface of the anvil is guided against the undersides of the top wall of the base at the opposite sides of the opening 93 as shown in Figs. 28, 29 and 31. A sheet metal spring 96 (Figs. 29, 32 and 33) is notched from its opposite ends as shown at 97 leaving the central portion 98. The forked portions on the opposite sides of this portion 98 are curved upwardly as shown at 99. The free ends of forked portions 99 rest on top of the lugs 94 as shown in Figs. 29 and 30 and the curved tops of these forks 99 engage against the underside of the anvil 88. A selecting pin 100 is placed in the notches 97 extending transversely of the central portion 98 and is supported by this central portion as shown in Figs. 29 and 30 while its opposite free ends are located between the lugs 94 as shown in Figs. 27 and 29. The edges of the flanges 95 of the anvil are provided with spaced notches 101 to receive the pin 100 to hold this anvil in the two positions, one when the notches 90 of the anvil are in alignment with the driver and the other when the notches 91 and 92 are in alignment with the driver. Thus the anvil can be slid between the two positions and will be retained therein by the pin 100. To facilitate shifting of the anvil it may be scored or roughened as indicated at 102 in its upper surface to give a suitable finger grip. To enclose the lower portion of the anvil to protect it and also to give a rubber foot for the base of the machine, a rubber block 103 is shaped at its upper side to fit within the front end of the base 89 and it is recessed at its upper side as indicated at 104 to enclose the supporting devices for the anvil. To retain this rubber foot in place integral lugs 105 are bent downwardly from the top wall of the base, these being provided when the opening 93 is made in this wall, and they may be forced into the rubber block to hold it in position.

The whole body 1 is removably secured to the base 89 so that it may be readily attached or detached. For this purpose the rear end portion of the top wall of the base is cut, a pair of laterally spaced ears 106 (Figs. 1 and 14) are bent upwardly therefrom and a transverse pivot pin 107 is mounted therein. Cooperating with this pin to secure the body to the base is a reenforcing channel 108 (Figs. 2, 4, 14 and 24 to 26.) This is a stamping of suitable gauge metal of substantially inverted U-shape having a top wall 109 and the side walls 110 being spot welded to downwardly extending ears 110a on side walls 2 and 3 of the body (Figs. 11 and 14) as shown at 110b. The side walls 110 are provided with an L-shaped or bayonet slot 111 to receive the pin 107, and at the inner end of this slot is a notch 112 into which the pin 107 may seat as shown in Figs. 2 and 4. A body lift spring 113 is secured to the underside of the top wall of the base by any suitable means, such as a screw or rivet 114, and at its free end is cut to form fingers 115 to engage the under edges of the walls 110 of the reenforcing channel 108 and hold the body upwardly so that the pin 107 is seated in the notches 112 and to prevent the body from becoming accidentally detached from the base. These fingers also hold the front end of the body 1 elevated above the anvil 88 as shown in Figs. 1 and 2 so that the articles to be stapled may be inserted. The portion

of the spring 113 between the fingers 115 is made substantially T-shaped as shown at 116 (Fig. 27) and is seated in a similarly shaped recess 117 in a rubber foot 118 shaped on its upper wall to fit in the rear end portion of the base 89. The fingers 115 seat in a recess on a top wall of this rubber foot as shown in Fig. 14 and thus with the portion 116 retain the rubber foot in position. If it is desired to remove the body 1 from the base all that is necessary is to press downwardly on the rear end portion of the body to depress the side walls 110 away from the pin 107, and then by drawing the body forwardly this pin can be passed out through the slots 111 removing the body from the base. To mount the body on the base a reverse operation is all that is necessary.

It will thus be seen that this staple driving machine is made almost entirely of press work stamped from suitable gauge metal and formed to shape, and then is assembled principally by spot welding. It is also of simple construction, being composed of relatively few parts, and the fact that it is made of stampings makes it of light weight and strong. To refill with a new strip of staples all that is necessary is to release the lever 52 when the staple guide or slide 20 will be automatically projected a short distance and may be then drawn to the full extended position of Figs. 7 and 8 to permit a new strip of staples 21 to be placed on top of the slide. Then the slide may be pushed back into its normal position of Fig. 2 where it will be retained by the lever 52.

Having thus set forth the nature of our invention, what we claim is:

1. A staple driving machine comprising a body, a staple slide mounted in the lower part of the body to slide forwardly from the body for loading with staples, a releasable catch for normally retaining the slide in the body, a staple guideway for staples to be driven at the front end of the slide, a staple driver operable through the guideway, a hand lever pivoted in the body and connected with the driver for operating it, and a spring reacting between the hand lever and the catch to retain both in their normal positions.

2. A staple driving machine comprising a sheet metal body having spaced side walls, a staple slide mounted in the lower part of the body between the side walls and projectable from the front thereof for loading with staples, a staple guideway at the front end of the slide, means for feeding staples along the slide to the guideway, a staple driver operable in the guideway, a hand lever pivoted in the body formed of sheet metal of substantially inverted U-shape and having notches in the forward ends of the side walls for mounting the driver, and a spring tending to hold the lever and driver in elevated position.

3. In a staple driving machine, a body, a staple slide in the body and a staple guideway at the front of the slide, means for feeding staples along the slide to the guideway, a staple driver operable in the guideway, a hand lever having spaced upright side walls having notches in their forward ends providing projecting lugs at the lower sides of the notches, said driver having notches in its opposite side edges, and the upper end portion of the driver being seated in the notches in the side walls of the lever with the lugs in the notches in the side walls of the driver.

4. A staple driving machine comprising a sheet metal body having spaced side walls, a staple slide in the lower part of the body having a staple guideway at the forward end thereof, means for

feeding staples along the slide to the guideway, a hand lever pivoted to the side walls of substantially inverted U-shape in cross section, a staple driver operable in the guideway and connected to the side walls of the handle, a cross wall between the side walls of the body, a stop projecting upwardly from said cross wall, the forward end of the top wall of the lever being extended downwardly and rearwardly to engage said stop to limit upward movement of the lever, and a spring for normally holding the lever in elevated position.

5. In a staple driving machine, a body having spaced side walls, a staple slide in the lower part of the body, a staple guideway at the forward end of the slide, means for feeding staples along the slide to the guideway, a staple driver operable through the guideway, an operating lever of sheet metal and of substantially inverted U-shape in cross section having downwardly projecting side walls, means for mounting the driver on the forward ends of the side walls on the lever, the rearward ends of said latter walls being extended toward each other and then side by side to form a lug, and a spring seated on said lug and tending to hold the lever in elevated position.

6. A staple driving machine comprising a body having spaced side walls, a staple slide mounted between said side walls and movable forwardly from the body for loading of staples, a staple guideway at the front of the slide, a staple driver operable in the guideway, an operating lever pivoted in the body and connected with the driver for operating it, a release lever pivoted in the body and normally engaging a shoulder on the slide to retain it in the body, said operating lever and said release lever having lugs extending toward each other, and a spring mounted on said lugs and tending to move the levers to normal position.

7. A staple driving machine comprising a body, a staple slide mounted in the body and slidable to a projected position for loading with staples, said slide being of substantially U-shape in cross section, a substantially U-shaped support secured to the forward end of the slide, a front plate mounted on said support and spaced from the end of the slide to form a staple guideway, a front plate cover embracing the plate and secured to the support, a substantially flat staple driver operable in the guideway, and a pivoted lever mounted in the body and connected with the driver to operate it.

8. A staple driving machine comprising a body having spaced side walls provided with notches in their lower edges, a sheet metal substantially rectangular housing mounted in the lower part of the body and having laterally extending lugs seated in said notches, said housing being secured to the side walls, a staple slide mounted in the housing and projectable forwardly therefrom for loading with staples, a staple guideway at the forward part of the slide, a staple driver operable in the guideway, and means for operating the driver.

9. A staple driving machine comprising a sheet metal body having spaced side walls provided with notches in their lower edges, a sheet metal housing comprising top and side walls with inwardly projecting flanges at the lower edges of the side walls, said flanges being spaced from each other to provide a guide channel, said flanges having laterally extending lugs seated in said notches and the housing being welded to the side walls of the body, a staple slide mounted in

the housing and projectable therefrom for loading with staples, a staple guideway at the front of the slide, guide lugs on the slide projecting into the channel, means to feed staples along the slide to the guideway, a staple driver operable in the guideway, and means for operating the driver.

10. A staple driving machine comprising a body having spaced side walls, an elongated slide housing mounted in the lower part of the body, a staple slide mounted in the housing and slidable forwardly in the housing for loading of staples, a staple guideway at the forward end of the slide, a staple driver operable in the guideway, releasable means normally retaining the slide in its innermost position in the housing, a spring to move the slide forwardly when said means is released, and a brake spring carried by the slide and frictionally engaging the housing to retard forward movement of the slide.

15. 11. A staple driving machine comprising a body having spaced sheet metal side walls connected by an integral front wall, a slide housing mounted in the lower part of the body having a top wall, a staple slide mounted in the housing, a staple guideway at the front end of the slide, means for feeding staples along the slide to the guideway, a staple driver operable in the guideway, the forward end of the top wall of the housing being extended upward to form a guide for the driver at the rear thereof, and the lower end of the front wall of the body being extended backward and laterally to form a guide at the front of the driver.

20. 12. A staple driving machine comprising a body having spaced side walls, a slide housing mounted in the body at the lower part thereof, a staple slide mounted in the housing and projectable forwardly therefrom for loading of staples, a staple guideway at the forward end of the slide, a follower on the slide for feeding staples to the guideway, the housing having a rear wall at the inner end of the slide, a follower rod secured to this wall and extending longitudinally of the slide, a spring on the rod tending to advance the follower, a staple driver operable in the guideway, and means for operating the driver.

25. 13. A staple driving machine comprising a body having spaced side walls, an elongated slide housing mounted in the lower part of the body having a top wall, a staple slide mounted in the housing and slidable forwardly in the housing to staple loading position, a staple guideway at the forward end of the slide, a staple driver operable in the guideway, releasable means normally retaining the slide in its innermost position in the housing, a spring to move the slide forwardly when said means is released, and a brake spring carried by the slide, said brake spring comprising a looped wire with its sides pivoted in the sides of the slide and its connecting loop portion frictionally engaging the top wall of the housing.

30. 14. A staple driving machine comprising a body having spaced side walls, an elongated slide housing mounted in the lower part of the body, a staple slide mounted in the housing and slidable forwardly in the housing for loading of staples, a staple guideway at the forward end of the slide, a staple driver operable in the guideway, releasable means normally retaining the slide in its innermost position in the housing, said housing having a wall projecting across the inner end of the slide, and a slide ejector spring mounted between the inner end of the slide and said wall of

the housing to move the slide forwardly when released.

15. A staple driving machine comprising a sheet metal body having spaced side walls connected by an integral front wall, a sheet metal slide housing having top, side and bottom walls, said housing being located between the side walls of the body and welded thereto, a staple slide mounted in the housing and projectable from the

front thereof for loading staples, a staple guideway at the forward end of the slide, a staple driver operable in the guideway, a sheet metal lever of substantially inverted U-shape in cross section, means for connecting the driver with the lever, and a sheet metal cover embracing the lever and welded to the top wall thereof.

FRIDOLIN POLZER,
ROY E. PETERSON.
